(57) **CLAIM**

The ornamental design for a bagged ice dispensing machine, as shown and described.

DESCRIPTION

FIG. 1 is a top-left-front perspective view of a bagged ice dispensing machine showing my new design, according to a first embodiment;

FIG. 2 is a front elevational view of the first embodiment; FIG. 3 is a top-left-front perspective view of the bagged ice dispensing machine showing my new design, according to a second embodiment; and,

FIG. 4 is a front elevational view of the second embodiment. The broken lines in the FIGS. 1-4 show portions of the bagged ice dispensing machine that form no part of the claimed design.

All other perspective views, and all other orthogonal views, of the bagged ice dispensing machine are not shown and form no part of the claimed design. Any surface, or any portion of any surface, of the bagged ice dispensing machine not shown in FIGS. 1-4 forms no part of the claimed design.
